A. C. HERZBERG

GARTER

Filed April 24, 1924

UNITED STATES PATENT OFFICE.

ALBERT C. HERZBERG, OF MEMPHIS, TENNESSEE.

GARTER.

Application filed April 24, 1924. Serial No. 708,630.

To all whom it may concern:

Be it known that I, ALBERT C. HERZBERG, a citizen of the United States, residing at Memphis, in the county of Shelby and State of Tennessee, have invented certain new and useful Improvements in Garters; and I do hereby declare the following to be a full, clear, and exact description of the invention, such as will enable others skilled in the art to which it appertains to make and use the same, reference being had to the accompanying drawings, and to characters of reference marked thereon which form a part of this specification.

15 This invention relates to improvements in men's garters or sock supporters for attachment to knee-length undergarments.

The invention has for its principal object to provide a non-restrictive sock supporter or garter especially adapted for attachment to the lower ends of knee-length undergarments, whereby the supporter or garter is suspended at the side of the wearer's leg so that its lower end is conveniently positioned for operative attachment to the top of the wearer's sock. The invention has for a further object to provide a garter of the kind mentioned, which is self-adjustable to the bending of the leg of the wearer when walking or sitting, and which, nevertheless, provides a taut support for keeping the sock pulled up without discomfort to the wearer, or without undue strains upon either the undergarment or the sock, which would be likely to tear or injure the fabrics thereof. My novel garter structure is designed to provide additional advantages by reason of the arrangement and correlation of its parts whereby, when the wearer is seated and the leg is bent, resulting in a shortening of the distance between the undergarment and sock, any looseness or slackness is taken up by the bend or gathering of the outer trousers under the knee, which causes the garter body portions, where joined by the compensating ring, to bend or curve around the angle formed by the thus gathered portions of the trousers, thereby permitting a natural and easy automatic adjustment of the garter to all positions of the leg without loss of desired supporting tautness, and yet without undue strain likely to pull the undergarment into uncomfortable positions. The garter structure is so arranged that in use it may be left attached to the undergarment when detached from the sock in undressing,

and is consequently always conveniently ready for use when the wearer resumes the garments.

Other objects of this invention, not at this time more particularly enumerated, will be clearly understood from the following detailed description of the same.

With the various objects of the invention in view, the same consists in the novel construction of men's garter hereinafter set forth; and, the invention consists, furthermore, in the novel arrangements and combinations of the various devices and parts thereof, as well as in the details of the construction of the same all of which will be fully described in the following specification, and then finally embodied in the appended claim.

The invention is clearly illustrated in the accompanying drawings, in which:—

Figure 1 is a perspective view showing the application of the novel garter to the garments of the wearer when in use, and showing the disposition and functioning of the same when the wearer's leg is bent. Figure 2 is a side elevation of the wearer's leg, showing the disposition and operative arrangement of the garter between the knee-length undergarment and sock, and more particularly the position assumed by the garter when the wearer is standing. Figure 3 is an enlarged fragmentary view, showing the compensating ring which operatively joins the upper and lower body portions of the garter together; Figure 4 is a side view of a knee-length undergarment, showing how the garter remains conveniently attached thereto when the same is removed from the person of the wearer; and Figure 5 is a face view of the novel garter modified to provide a single sock grip instead of a double grip.

Similar characters of reference are employed in all of the hereinabove described views, to indicate corresponding parts.

Referring now to said drawings, the reference character 6 indicates the main body or lower member of the garter structure, which is preferably made of a length of elastic webbing, which is doubled upon itself to pass its upper end through a compensating and articulating ring 7. The body or member 6 is provided with a buckle or clasp 8, which cooperates with the doubled portions thereof, so as to permit of the regulation or adjustment of the length of

body or member 6, as the conditions of use thereof may require, all in the manner familiar to those skilled in the garment supporter art. Connected with the lower 5 end of said body or member 6, in any suitable manner, as, e. g. by means of a coupling member 9, is a sock fastener member, either in the form of a double grip member 10, as shown in Figures 1 to 4 inclusive, or 10 in the form of a single grip member 11, as shown in Figure 5. The fastener devices or grip members per se, may be of any well known form or construction, such as the button member 12 and associated separable 15 loop-member 13, as shown in the drawings.

The reference character 14 indicates a supporter member which is slidingly passed through the upper side of the compensating and articulating ring 7, so as to be doubled 20 therethrough and thus provide a pair of upwardly extending and somewhat divergent arms 14' and 14''. The supporter member 14 is thus arranged so that it will freely slide through the ring 7, and will also turn 25 on the ring as a fulcrum. The respective arms 14' and 14'' are each provided at their free extremities with fastener devices or grip members 15, which may be of any well known form or construction, but preferably 30 are of the same character or kind as the above described sock fasteners, viz, comprising a button member and an associated separable loop-member.

While I have described in detail one 35 garter or supporter device, it will be understood that the same are used in pairs, providing a supporter for each sock of the wearer.

In utilizing the garters, the same are attached respectively to the lower marginal 40 extremities of a knee-length undergarment 16, by means of the fastener devices or grip members 15, so that the supporter member 14, as coupled with the main body or lower member 6 by the compensating and articulating ring 7, is suspended from the knee-length undergarment, whereby the sock grip members or fastener devices are positioned 45 for operative attachment to the socks 17. In attaching the garter or supporter in the general way above mentioned, the fastener devices or grip members 15 are secured to the fabric of the undergarment 16, at the outer side of the garment leg, and respectively on opposite sides of the outer leg seam 50 of said garment, thus suspending the garter for downward extension along the outer side of the wearer's leg, with the compensating and articulating ring 7 substantially aligned with or opposite the knee 55 joint of the wearer's leg. The main body or lower member 6 may then be adjusted to the desired length, whereby the sock grip members are conveniently disposed for attachment to the upper marginal portion or 60 top of the wearer's sock 17, as shown in

Figure 2. It will be found in the actual wearing of my novel garter structure, the two attached extremities of the supporter member 14, to wit the arms 14' and 14'', function in a manner to provide two very 70 important self-adjustments relative to the garments and the leg of the wearer, when the leg is straight as in standing, or when bent, as in sitting. When the wearer is standing, said attached extremities of the arms 14' and 14'', being connected with the soft fabric of the undergarment, will tend to draw together, thus tending to lengthen the supporter member 14 under such conditions; when the wearer is seated, or when 75 crossing the legs, so that the legs are bent at the knee, the fabric of the undergarment tends to draw laterally across the leg, whereby said attached extremities of the arms 14' and 14'' tend to separate or diverge into a V-shape, thus shortening the supporter 80 85 90 95 100 105 110 115 120 125 130 member 14, and constituting one of the factors whereby the garter is self-adjusting to accommodate the same to the bent leg position of the wearer, without, on the one hand, undue slackening of the garter from the desired reasonably taut extension between undergarment 16 and sock 17 when the leg is bent, and on the other hand, without too great an increase of tautness or tension when the leg is straight. In addition to the tendency of the supporter member arms 14' and 14'' to diverge when the wearer's leg is bent, the supporter member 14 will also slide compensatingly through the ring 7 to alter the relative lengths of the arms 14' and 14'', as the pull on the garter may require when the wearer's leg is bent.

In my novel structure there is another factor which operates to make the garter automatically or self adjustable to the bent leg position of the wearer, without loss of a desirable degree of tension necessary to the smooth upholding of the sock under such conditions. This factor is due to the articulation provided between the supporter member 14 and the main body or lower member 6 of the garter by the compensating and articulating ring 7. As already intimated above, when the wearer's leg is bent, the distance between the lower extremity of the undergarment 16 and the top of the sock 17 is shortened, which, in the absence of compensating features, would unduly slacken the garter. This tendency to slackening of the garter is substantially prevented by the divergence of the arms 14' and 14'' resulting in the shortening of the supporter member 14 in the manner above described, but in addition to this it will be found that when the leg is bent the outer trousers 18 will gather or bunch up under the knee, which will tend to hold the ring 7 upward against the side of the knee, so that the supporter member 14 and main body 6 turn or swing

on the ring 7 as a fulcrum, to thus cause the garter as a whole to bend around the angle formed by the bent leg, as shown in Figure 1, thus further guarding against undue slackening of the garter.

From the above description it will be understood that my novel garter structure possesses a distinctive and new mode of operation, the dominating factor of which resides in the interconnection of the main member 6 with a supporter member 14 for attachment to a knee length undergarment by means of the ring 7, in such manner that not only will the supporter member 14 compensatingly slide lengthwise through the ring, but the ring will also form a hinge or articulation between the parts which serves as a fulcrum on which the respective parts may swing to bend the garter as a whole relative to the angle formed when the wearer's leg is bent. It will thus be apparent that I have provided a non-restrictive garter, from which all parts tending to encircle or compress the wearer's leg have been eliminated, so that free circulation of blood through the leg is unimpaired; the garter also is comfortable and convenient, and may be left attached to the undergarment when the latter is removed and consequently always conveniently at hand when the clothes are resumed; and finally, the garter is efficiently self-compensating or adjustable whereby the same readily and quickly accommodates itself to all positions of the

wearer's body and legs in walking, bending, sitting, running, ascending and descending stairs, et cetera.

Having thus described my invention, I claim:

In men's hose supporters for use with knee-length undergarments, the combination with an articulating ring, of an upper supporter member doubled on itself and slidably engaged through said articulating ring to provide relatively short upwardly extending divergent arms, gripping means connected with the free end of each arm to individually fasten said arms at separate points to the end of the leg portion of a knee-length undergarment so that the same are capable of sidewise movement toward and away from one another and at the same time so suspend the supporter member as to dispose said articulating ring adjacent to the bend of the knee of the wearer, a body member suspended from the underside of said articulating ring for sidewise swinging movement thereon, means connected with the lower end of said body member to engage and hold a sock, and said body member having means for adjusting its length to properly position said sock holding means relative to the sock top of the wearer.

In testimony, that I claim the invention set forth above I have hereunto set my hand this 17th day of April, 1924.

ALBERT C. HERZBERG.
